ELECTRICAL CONNECTION MEANS

Harry A. Douglas, Bronson, Mich., assignor to
Kingston Products Corporation, a corporation
of Indiana

Application August 23, 1935, Serial No. 37,490

8 Claims. (Cl. 173—328)

My invention relates to electrical connection means, and more particularly to means for receiving conductor terminals of the snap type, and the principal object of my invention is to provide new and improved electrical connection means of these types.

In the drawing accompanying this specification and forming a part of this application, I have shown, for purposes of illustration, several forms which my invention may assume, and in this drawing:

Figure 1 is a perspective view of one embodiment of my invention;

Figure 2 is an enlarged longitudinal section of the embodiment shown in Figure 1, and including, in addition, a plug conductor terminal adapted to cooperate therewith;

Figure 3 is a perspective view of the embodiment shown in Figure 1 taken at a different angle, and showing the parts thereof in disassembled relation;

Figure 4 is a perspective view of a different embodiment of my invention; and

Figure 5 is a perspective view of another embodiment of my invention.

Referring to Figures 1, 2, and 3 of the drawing, there is here shown a terminal post 10, suitably mounted on a base 11, the base being fragmentarily shown. The terminal post 10 comprises a body portion 12, here shown as being formed of a single piece of channel stock bent into a generally right angular formation, and including a generally vertical wall 13 and a generally horizontal wall 14, the latter wall serving as a foot for the body portion 12, and being integral with the vertical wall 13 and extending at right angles therefrom at the lower end thereof.

The vertical wall 13 is provided with a composite aperture 15 which includes an arcuate recess 16, forming the upper end of the composite aperture 15, and a generally rectangular aperture 17, extending from the arcuate recess 16 to a plane including the lower surface of the horizontal wall 14. The generally rectangular aperture 17 is of greater width than the width or diameter of the arcuate recess 16, and at its upper part, as viewed in Figure 1, is provided with curved marginal walls 18, merging with the arcuate recess 16. Substantially circumscribing the recess 16 is a laterally extending arcuate flange 19 having its inner surface continuous with the recess 16. The flange 19 may be formed by drawing out the metal theretofore forming part of the vertical wall 13 which had been removed to form the arcuate recess 16.

The horizontal wall 14 is provided with a relatively narrow slot 20 communicating with the generally rectangular slot 17 and extending transversely substantially the distance between the channel walls of the body member 12. The slot 20, as best seen in Figure 3, is of greater transverse extent than the rectangular slot 17. The foot or horizontal wall 14 may be provided with an aperture 21, spaced from the slot 20, through which a screw 22 or any other suitable fastening means may be disposed, to fasten the body portion to the base 11. The foot 14 may be prevented from turning about the fastening means 22 by a projection 23, struck downwardly from the foot 14, the projection being adapted to be disposed in a recess 24 formed in the upper surface of the base 11.

Detent means 25 are adapted to cooperate with the composite aperture 15, and comprise a body portion generally of U-shape and of a width greater than the thickness of the wall 13, so that when the detent means 25 are in position with respect to the body portion 12, portions thereof will be disposed on opposite sides of the body portion. The body portion of the detent means 25 includes a bight 26, joined at opposite margins to legs 27 and 28. Each of the legs 27 and 28 is provided with pairs of spaced fingers 29 and 30, the fingers 29 being positioned adjacent the ends of the legs 27, 28, and formed by a longitudinal slot 31 in each leg, and bent outwardly at right angles to the longitudinal extent of each leg 27, 28. The fingers 30 are located adjacent the bight 26 and may be formed as relatively narrow projections of the transverse width of the detent means 25, the fingers being bent at right angles to the transverse extent of the detent means 25. The space between each pair of fingers 29—29 and 30—30 is substantially equal to the thickness of the vertical wall 13. The bight 26 of the detent means 25 is provided with a substantially semi-spherical protuberance 32, here shown as being struck out from the metal forming the bight 26.

The detent means 25 are adapted to be slidably disposed in the composite slot 15, and when so disposed, the detent means are normally positioned adjacent the recess 16, with the protuberance 32 extending into the recess 16, and the surfaces of the bight 26 engaging the curved marginal walls 18 of the composite recess. In this position the detent means 25 are thereby limited in upward movement. The fingers 29 and 30 straddle the thickness of the wall 13 adjacent the composite

slot 15 and thereby prevent transverse movement of the detent means 25.

Biassing means are provided to bias the detent means 25 into cooperative position with respect to the body portion 12, and include a leaf-spring like member 33 shaped double-ogee in longitudinal section. The spring member 33 comprises substantially plane ends 34 and 35, and loops 36, 37, and 38. Each of the loops 36, 37, 38, and the free portion of the ends 34 and 35 is provided with a relatively narrow central slot 39 of a width to freely pass the thickness of the wall 13. The end 35, shown in Figure 1 to be the upper end, of the spring member 33 is formed with a substantially semi-spherical protuberance 40, here shown to be struck out from the end 35, intermediate the loop 38 and the free portion of the end 35. The spring member 33 is of greater width than the thickness of the wall 13, so that when the biassing means are in position with respect to the body portion 12, portions thereof will be disposed on opposite sides of the wall 13.

To assemble the terminal post 10, the detent means 25 are slidably inserted into the composite aperture 15, the transverse slot 20 in the horizontal wall 14 permitting such insertion, until the adjacent surfaces of the bight 26 abut the curved marginal walls 18. The biassing means are then inserted in the composite aperture 15, the leg 35 being inserted first, into abutting engagement with the lower surfaces of the fingers 29 formed on the legs 27, 28. In this position, the protuberance 40 formed in the end 35 projects within the space defined by the inner surface of the detent means 25, and the lower surface of the leg 34 lies generally in a plane including the lower surface of the horizontal wall 14. The fastening screw 22 is then inserted through the aperture 21 and its screw-threaded end is engaged with a screw-threaded aperture formed in the base 11. The parts comprising the terminal post are then securely held in assembled relation by reason of the fact that both the body portion 12 and the biassing means 33 are supported by the base 11.

It will be appreciated that the parts of the detent means 25 and spring member 33 extending from the right hand surface of the vertical wall 13, as viewed in Figure 2, are substantially disposed within the confines of the channel portions of the vertical wall 13.

In Figure 2 there is shown a plug conductor terminal 41 of the snap type, adapted to be inserted either into the recess 16, or into the recess formed by the inner surface of the detent means 25. The plug terminal 41 comprises a generally cylindrical surface 42 formed with an annular furrow 43. The plug conductor terminal 41 is formed with a frustro-conical end 44, and the plug terminal may be fastened to a conductor disposed therein, as by swaging, indicated by the wedge indentations 45 in the frustro-conical end 44.

To engage the plug conductor terminal 41 with the upper terminal receiving aperture, the frustro-conical end 44 is inserted into the recess 16, causing the surface of the frustro-conical end to cam the detent means 25 downwardly, as viewed in Figure 1 to provide for the accommodation of the cylindrical portion 42, the detent means in turn forcing the end 35 of the spring member 33 downwardly and thereby compressing the spring member, the slots 39 being of sufficient length to permit transverse spreading of the spring member. Further inserting move-

ment of the plug conductor terminal 41 causes the protuberance 32 of the detent means 25 to snap into the annular furrow 43 and thereby hold the plug conductor terminal in operative position.

The plug conductor terminal may also be engaged in the lower terminal receiving aperture, and this engagement is effected by inserting the frustro-conical end 44 into the space defined by the inner surface of the detent means 25, the detent means being held against upward movement by reason of the abutment of the outer surface of the bight 26 with the curved marginal walls 18 of the generally rectangular aperture 17. The frustro-conical end 44 therefore cams the end 35 downwardly and compresses the spring member 33, further inserting movement causing the protuberance 40 on the end 35 to snap into the annular furrow 43. It will be understood that the terminal post 10 may receive and hold a conductor terminal in either its upper or lower terminal receiving recess, or in both of them, equally well.

Referring to Figure 4, the embodiment therein shown comprises a terminal post 46 suitably mounted on a base 47. The terminal post 46 includes a body 48 shaped similarly to the body 12 of the terminal post 10, but in this instance the vertical wall 49 is of lesser extent than the vertical wall 13. A composite aperture 50 is provided in the wall 49, and includes an arcuate recess 51 similar to the recess 16 of the post 10, and a rectangular aperture 52 of greater width than the width or diameter of the recess 51, and communicating therewith at its upper end. The rectangular aperture 52 forms shoulders 53 with the recess 51 adjacent the points of communication therewith.

Biassing means are provided to cooperate with the body portion 48 and include a leaf-spring like member 54 similar to the spring member 33 of the post 10, with the exception that the spring member 54 is provided with only two spring loops and is therefore S-shaped. An end 55 carries a substantially semi-spherical detent 56 extending upwardly from the surface of the end 55, as viewed in Figure 4, and projecting into the space defined by the recess 51. It will be noted that in this embodiment, detent means similar to the detent means 25 are omitted. Slots similar to the slots 39 of the spring member 33 are formed in the spring member 54, the slots in this instance closely but slidably fitting the marginal walls of the rectangular aperture 50.

To assemble the terminal post 46, the spring member 54 is inserted into the composite aperture 50, a transverse slot in the horizontal wall similar to the transverse slot 20 providing for such insertion, until the end 55 of the spring member 54 abuts the shoulders 53. In this position the opposite end of the spring member will be substantially in the plane including the lower surface of the horizontal wall, and fastening means, similar to the fastening means 22 may be used to assemble the terminal post 46 with the base 47. As in the embodiment disclosed in Figures 1, 2, and 3, portions of the spring member 54 are disposed on opposite sides of the vertical wall 49.

A plug conductor may be engaged by the terminal post 46, the frustro-conical end of the plug conductor, upon inserting movement into the recess 51, camming the end 55 of the spring member 54 downwardly, the protuberance 56 on the end 55 snapping into the annular furrow 75

when the latter is in proper relation with respect to the protuberance 56.

In the embodiment shown in Figure 5, a terminal post 57 includes a body portion 58 suitably mounted on a base 59. The body portion 58 in this instance, is formed of plane sheet metal bent to a right angular formation to provide a vertical wall 60 and a horizontal wall 61. The vertical wall 60 is formed with a composite aperture 62 comprising an arcuate recess 63 and a rectangular aperture 64, the latter being of a greater width than the recess 63, and forming shoulders 65 therewith.

Biasing means are provided for cooperation with the body portion 58, and comprise a leaf-spring like member 66, shaped similar to the spring member 33 of the terminal post 10, but in this instance both ends are plane in extent. The spring member 66 may be assembled with the body by inserting the spring member 66 into the composite slot 62 until an end thereof abuts the shoulders 65. The terminal post 57 may then be secured to the base 59 by fastening means similar to the fastening screw 22 of the terminal post 10.

A plug conductor terminal may be engaged by the terminal post 57, the frusto-conical end thereof being inserted into the recess 63 to cam the plane surface of the adjacent end of the spring member 66 downwardly, thereby compressing the latter. Further inserting movement brings the annular furrow in alignment with the marginal walls of the recess 63, and the spring member snaps the annular furrow into engagement with the marginal walls to thereby yieldably hold the plug conductor terminal in position with respect to the terminal post 57.

From the foregoing it will be apparent to those skilled in the art that the illustrated embodiment of my invention provides a new and improved electrical contact and connection means, economical in construction and assembly, and accordingly, accomplishes at least the principal object of my invention. It further will be obvious to those skilled in the art that the illustrated embodiment of my invention may be variously changed and modified without departing from the spirit of my invention, or sacrificing all of the advantages thereof, and that accordingly, the disclosure herein is illustrative only, and my invention is not limited thereto.

I claim:

1. Receptacle means, comprising: a body portion, having a recess for receiving a conductor terminal, and also having an elongated aperture communicating with said recess; and biasing means cooperable with said body portion recess to provide means for yieldably holding a conductor terminal in operative position in said recess, said biasing means including a looped leaf spring provided with recesses in the loops and extremities thereof, said recesses cooperating with marginal surfaces of said elongated aperture to provide for guiding of said biasing means.

2. Receptacle means, comprising: a body portion, having a recess for receiving a conductor terminal, and also having an elongated aperture communicating with said recess; biasing means, including a looped leaf spring provided with recesses in the loops and extremities thereof, said recesses cooperating with marginal surfaces of said elongated aperture to provide for guiding of said biasing means; and detent means, having portions engageable with marginal surfaces of said elongated aperture to provide for guiding of said detent means, said detent means being

acted upon by said biasing means and moved to cooperative position with respect to said body portion recess, and said biasing means having a portion in cooperable relation with said detent means recess.

3. Receptacle means, comprising: a body portion, having a recess for receiving a conductor terminal, and also having an elongated aperture communicating with said recess; biasing means, comprising a looped leaf spring provided with recesses cooperable with marginal surfaces of said elongated aperture so as to guide said biasing means, one leg of said leaf spring being cooperable with said body recess and engageable with a conductor terminal disposed in said recess to bias the conductor terminal toward a margin of said recess and thereby yieldably hold the conductor terminal in operative position.

4. Receptacle means, comprising: a wall, having an elongated aperture extending from one end of said wall toward the other end, and at this other end having a marginal recess for receiving a conductor terminal; a member, disposed within the confines of said elongated aperture, having guiding fingers engaging opposite lateral surfaces of said wall, to hold said member for sliding movement along said wall, said member having a portion directed toward said recess, and a recessed portion for receiving a conductor terminal; and a looped leaf-spring, comprising relatively movable portions, slotted in the loops and ends to slidably fit the marginal surfaces of said elongated aperture, one end being held against movement with respect to said wall, and the other end bearing against said member, and urging said member to yieldably engage a conductor terminal disposed within said wall recess, said end being positioned adjacent said member recess, and being constructed and arranged to yieldably engage a conductor terminal disposed in said member recess.

5. Receptacle means, comprising: a pair of angularly disposed walls, one being provided with an elongated aperture extending from the other wall toward the end of said one wall, and at this end having a recess in its margin for receiving a conductor terminal, and said other wall having a slot communicating with said elongated aperture, and being adapted to be secured to a support; and biasing means, comprising a looped leaf-spring having slots in its loops and extremities, the marginal surfaces of said slots slidably engaging the marginal surfaces of said elongated aperture; the slot in said other wall permitting assembly of said leaf-spring so that parts of said spring are disposed on opposite sides of said one wall, said leaf-spring having one end urged toward the recess in said elongated aperture, and its other end being adapted to bear against the support to which said other wall is secured.

6. Receptacle means, comprising: a pair of angularly disposed walls, one being provided with an elongated aperture extending from the other wall toward the end of said one wall, and at this end having a recess in its margin for receiving a conductor terminal, and said other wall having a slot communicating with said elongated aperture, and being adapted to be secured to a support; detent means, having a recess for receiving a conductor terminal, and a portion cooperating with said wall recess, for holding a conductor terminal in position in said wall recess, said detent means having also guiding portions engaging marginal surfaces of said elongated aperture, to hold said detent means to sliding movement along

5 said wall; and biasing means, comprising a looped leaf-spring having slots in its loops and extremities, the marginal surfaces of said slots slidably engaging the marginal surfaces of said elongated aperture; the slot in said other wall permitting assembly of said detent means and said leaf-spring, so that parts of said detent means and said spring are disposed on opposite sides of said one wall, said leaf-spring having one end resiliently bearing against said detent means to urge 10 said detent means toward the recess in said elongated aperture, said one end being positioned adjacent said detent means recess to yieldably hold a conductor terminal in said detent means recess, and the other end of said spring being 15 adapted to bear against the support to which said other wall is secured.

7. Receptacle means, comprising: a wall, having an aperture, one margin of said aperture being formed with a recess for receiving a conductor terminal, said recess being reduced in size with respect to said margin to form shoulders; and spring means, comprising relatively movable portions, one end portion being held against movement with respect to said wall, and the other end portion having projections slidably engaging opposite lateral surfaces of said wall to hold said other end portion to slidable movement along said wall and toward and away from said recess; 20

said other end portion being biased toward said recess, and abutting said shoulders to limit its movement toward said recess.

8. Receptacle means, comprising: a wall, having an aperture, one margin of said aperture being formed with a recess for receiving a conductor terminal, said recess being reduced in size with respect to said margin to form shoulders; recessed detent means, having projections engaging opposite lateral surfaces of said wall adjacent 10 said aperture, to hold said detent means to sliding movement along said wall; and toward and away from said recess; and looped leaf-spring means, comprising relatively movable portions, slotted in the loops and ends to slidably fit around the marginal surfaces of said aperture so as to hold said spring means to movement along said wall, one end portion of said spring means being held against movement with respect to said wall, and the other end portion bearing against said 15 detent means, and biasing said detent means to abutment with said shoulders, said detent means being in position to yieldably engage a conductor terminal disposed in said wall recess; and said other end portion being constructed and arranged to yieldably engage a conductor terminal disposed in said detent means recess. 25

HARRY A. DOUGLAS.
